ORTHODONTIC DISPLAY MODEL

Bernard Geltzer, 8200 Ponce de Leon Road,
Miami, Fla. 33143

Filed Nov. 12, 1969, Ser. No. 20,049

Term of patent 3½ years

Int. Cl. D24—99

U.S. Cl. D24—1

FIG. 1 is a front perspective view of an orthodontic display model embodying my new design;

FIG. 2 is a perspective view taken from one side thereof; and

FIG. 3 is a perspective view taken from the side opposite that shown in FIG. 2.

I claim:

The ornamental design for an orthodontic display model, as shown.
